UNITED STATES PATENT OFFICE.

GEORGE W. FOTHERGILL, OF LOUISE, TEXAS.

MULTIPLANE BEVEL SQUARE.

Application filed June 24, 1926, Serial No. 118,293. Renewed May 1, 1928.

This invention relates to bevel squares and particularly to certain improvements on the structure shown in Patent No. 897,104 granted to Carl M. Hoeregott on August 25, 5 1908.

The general object of this invention is to so improve this bevel square that it will be more certain in its action, may be more readily adjusted, that the parts will be more positively held in their adjusted positions, that there will be less liability of wear and that the square will be rendered stronger and more rigid.

Another object is to so construct the square 15 that the marking blades thereon may be readily set without the necessity of using a steel square for the purpose.

Still another object is to so construct the bevel square that it may have a wider range 20 of use than was possible with the original structure.

My invention is illustrated in the accompanying drawings wherein:—

Figure 1 is a top plan view of a bevel 25 square constructed in accordance with my invention;

Fig. 2 is a perspective view of one of the supporting stems or slides;

Fig. 3 is a side elevation of the bevel 30 square, the lateral blade being in section at its rear end;

Fig. 4 is a section on the line 4—4 of Figure 3.

Fig. 5 is a section on the line 5—5 of Figure 3;

Fig. 6 is a section on the line 6—6 of Figure 3.

It will be seen that in general form the improved square is quite like the square illustrated in said patent. The body of the square is designated 10 and may be made of wood or other suitable material. The lower edge face of the body is straight and the body is bifurcated almost in its entire length 45 by a slot 11. Inserted in said slot is a blade 12 whose inner end is longitudinally slotted as at 13. The forward end of the body 10 is reduced in thickness and passing through this forward end is the bolt 14 carrying the wing nut 15. The slot 11 permits longitudinal adjustment of the blade 12 and the bolt 14 permits a rotary adjustment of the blade. Thus, the blade can be set at any desired bevel. The extreme forward end of 55 the blade is preferably inclined from its under edge to its upper or forward edge. Also

disposed within the slot 11 and extending from the rear end of the body nearly to the front end thereof is a tongue 16 which projects below the lower edge of the body as 60 shown in Figures 5 and 6. The forward end of the body is reduced in depth so as to form a throat 17 and the forward end of the tongue 16 is inclined upward and forward as at 18, this inclined end extending up into 65 the throat 17. This tongue 16 is held in place by screws or other equivalent means.

The side faces of the body 10 are channeled longitudinally for their entire length and disposed in each channel is a channel-shaped 70 wear plate 20, see Figures 5 and 6. At the throat 17 of the body, the lower flange of this channel-shaped wear plate is cut away as shown in Figure 4. Disposed in these channels are the longitudinally extending 75 flat stems 21 or shanks of supporting brackets 22, each at its forward end having an outstanding ear 23 apertured for the passage of a screw. These shanks 21 are held in sliding engagement within the channels 20 80 by longitudinally extending plates 24, each of which is held to the body by screws 25. The plate 24 at its forward end is cut away to provide a throat 26 and the upper margin of this throat is graduated as at 27, each 85 stem or shank 21 being provided with an indicating mark 28 which coacts with these graduations to provide a proper adjustment of the corresponding stem or shank. In order to hold the shank 21 and the bracket 22 in their adjusted positions I provide a transversely extending bar 29 held in place by a headed pin 30 which extends transversely through the body 10, through the tongue 16, through the plates 24, and through the bars 90 29, the heads of this pin being disposed in countersinks in the bars 29.

Passing through each bar 29 and having screw-threaded engagement therewith and with the plate 24 is a set screw 31 which when turned home, will engage the shank 21 and hold it in its adjusted position.

Pivotedly or slidably engaged with each ear 23 by means of a bolt 32 and wing nut 33, is a blade 34, each blade being longitudinally slotted as at 35 and the bolt 32 passing through this slot. The forward end of each blade is angularly beveled with reference to the longitudinal axis of the blade so as to provide a pointed extremity 36 and each 110 blade is preferably formed with a vertically extending flange 37 and a horizontal flange

38 or, in other words, with an angular margin. As will be seen from Figure 4, the head 32^a of the bolt 32 bears against the downwardly extending flange 37 and is thus held 5 from rotation. This aids in clamping the blade securely in its adjusted position and at the same time the angular margin strengthens the blade 34 and renders it more rigid and brings the marking edge of the 10 blade in line with the lower edge of the body 10. The blade 12 is preferably graduated in any desired fractions of an inch and the graduations 27 may be in any desired fractions of an inch.

15 It will be seen that with the construction illustrated either one or both of the blades 34 may be used in conjunction with the blade 12 to mark the angles of certain cuts much used by carpenters. By cutting away the 20 forward edge of the tongue 16 as at 18, the blades 34 may be readily swung into any adjusted position nearly at right angles to the body. By providing the graduations 27, the slides or shanks 21 carrying the blades 25 34 may be readily adjusted without the necessity of using a steel square and thus the forward ends of the blades 34 may be brought into any desired relation to the blade 12 and the point 36 of each blade 34 30 may be brought either into alignment with the forward edge of the blade 12 or the rear edge thereof. The shanks 21 are guided throughout nearly their entire length by operating in the channels 20 and, while freedom 35 of movement is secured for these shanks 21 when the set screws 31 are released, yet the shanks are held from any up or down movement. It is to be particularly noted that the forward end of the body 10 is at right 40 angles to the upper and lower edges of the body. This enables the blade 12 to be set at right angles to the body without the use of a steel square.

45 One of the faults of the construction illustrated in the patent referred to was that the shank supporting the lateral blade would spring when a pencil was drawn along the outside of the angular blade. This is entirely prevented with my improved construction 50 for the reason that the shank is supported along its entire length and is engaged over nearly its entire extent by the plate 24.

I claim:

55 1. In a bevel square, a body, a blade pivotally and slidably engaging the forward end of the body, the body being formed with a longitudinally extending groove on its side face, a shank slidably mounted in said groove and having a laterally projecting ear disposed in a plane at right angles to the 60 plane of the blade, a blade pivotally and slidably mounted upon said ear, a plate extending over the side face of the body and over said groove and the shank therein, and means extending through said plate and en-

gaging the shank to hold it in any desired adjusted position.

2. In a bevel square, a body, a blade pivotally and slidably engaging the forward end of the body, the body being formed with a longitudinally extending groove on its side face, a shank slidably mounted in said groove and having a laterally projecting ear disposed in a plane at right angles to the plane of the blade, a blade pivotally and slidably mounted upon said ear, a plate extending over the side face of the body and over said groove and the shank therein, and means extending through said plate and engaging the shank to hold it in any desired adjusted position, the forward end of the body being reduced in depth to form a throat, said groove intersecting said throat, and the forward end of the plate being reduced in depth, said reduced portion being graduated, the shank being provided with an index pointer coacting with said graduations.

3. In a bevel square, a body bifurcated longitudinally, a blade pivotally and slidably engaged with said body and having a portion disposed in said bifurcation, a tongue inserted in said bifurcation and projecting below the lower face of the blade, the forward end of the body being formed with a throat and the lateral faces of the body having longitudinally extending grooves, channel-shaped wear plates disposed in said grooves, plates disposed against the side faces of the body and rigidly engaged therewith, each of said plates at its forward end being formed to provide a throat less in depth than the depth of the throat on the body, sliding members having shanks disposed in said grooves and longitudinally adjustable therein, each of said members at its forward end being formed with a laterally projecting ear, means operating through said plates for holding the sliding members in adjusted positions, and blades pivotally and slidably engaged with said ears for movement in a plane at right angles to the plane of the first named blade.

4. A bevel square, including a body having a plane lower face, the sides of the body being longitudinally grooved, a shank slidably mounted in each groove, a scale plate disposed on each side face of the body and extending over said shank and groove, means for retaining said shanks in various adjusted positions relative to the plates, a laterally projecting ear on one end of each shank, and a blade slidably and pivotally engaged with said ear for movement in a plane parallel to the lower face of the body, the outer margin of the blade being offset below the body of the blade, the lower face of this offset portion being in the same plane as the lower face of the body.

5. In a bevel square, a body having a

plane lower face, a shank slidingly engaged with the body and being formed at its forward end with a laterally projecting ear at right angles to the lateral face of the body and lying in a plane parallel to the lower face of said body, a blade having a slot, the lateral edge of the blade extending downward and then outward, the outer margin of the blade being on a level with the lower

face of the body, and a bolt passing through 10 said ear and the slot and having a nut, one side face of the head of the bolt bearing flat against the downwardly extending portion of the blade whereby to prevent the nut from turning.

In testimony whereof I hereunto affix my signature.

GEORGE W. FOTHERGILL.
